(57) **CLAIM**

The ornamental design for a “lock smith utility kit”, as shown and described.

DESCRIPTION

FIG. 1 is a perspective view of a lock smith utility kit showing my new design in an open unfolded position; FIG. 2 is a perspective view shown in a closed and folded position;

FIG. 3 is a top plan view shown in an open unfolded position;

FIG. 4 is a bottom plan view thereof;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is a perspective view of the lock smith utility kit shown in a hanging position.

The broken line showing of environment in the drawings is for illustrative purposes only and forms no part of the claimed design.
